UNITED STATES PATENT OFFICE.

HANS P. CLAUSSEN, OF MILWAUKEE, WISCONSIN, ASSIGNOR TO THE BRUNO NORDBERG COMPANY, OF SAME PLACE.

FRICITION-CLUTCH.

SPECIFICATION forming part of Letters Patent No. 451,728, dated May 5, 1891.

Application filed September 13, 1890. Serial No. 364,836. (No model.)

To all whom it may concern:

Be it known that I, HANS P. CLAUSSEN, of Milwaukee, in the county of Milwaukee and State of Wisconsin, have invented certain new and useful Improvements in Friction-Clutches; and I do hereby declare that the following is a full, clear, and exact description of the invention, which will enable others skilled in the art to which it pertains to make and use the same, reference being had to the accompanying drawings, and to the letters of reference marked thereon, which form a part of this specification.

The main object of my invention is to provide clutches of the class herein shown with means of adjustment by a single operation, whereby the gripping-jaws will be caused to properly engage with the friction wheel or driver and to produce a uniform engagement of the friction-surfaces.

It consists, essentially, of the combination, with gripping mechanism substantially like that herein shown and described, of levers for operating the jaws fulcrumed to an axially-adjustable collar or sleeve, and of a radially-movable collar linked to said levers so as to produce an equal and uniform engagement of the friction-surfaces.

In the accompanying drawings like letters 30 designate the same parts in the several figures.

Figure 1 is an axial section of a clutch to which my improvements are applied. Fig. 2 is a cross-section on the line xx , Fig. 1. Fig. 3 is a similar section on the line yy , Fig. 1, 35 showing the clutch in connection with a pulley, and Fig. 4 is a detail showing a modification of the lever connections for operating the jaws.

A represents the friction wheel or driver 40 keyed or otherwise suitably fastened upon the shaft B, and formed or provided with a laterally-projecting flange or rim a .

C is a jaw-carrier comprising a hub c , which is keyed or otherwise fixed upon the shaft B' 45 and radiating arms $c' c'$, to which the jaws D are attached by a sliding connection, permitting of their radial movement into and out of engagement with the rim a of the friction wheel or driver.

50 E are levers fulcrumed to the arms $c' c'$,

and connected on opposite sides of their fulcrums with the shanks of the jaws D D in such manner that when the inwardly-projecting arms of said levers are carried toward the friction-wheel A the jaws D will be moved 55 into engagement with its rim a , and vice versa.

The foregoing parts constitute the main features of a well-known clutch, and I make no claim thereto *per se*.

F F are bell-crank levers, which are fulcrumed to a collar G, mounted and axially adjustable upon the hub c of the jaw-carrier C. The arms f of the levers F are arranged to engage with and operate by contact the levers E for the purpose of closing the jaws 60 D against the rim of the driver A, springs d or other devices being arranged to open said jaws. Instead of the levers F operating the levers E by contact, they may have a positive connection therewith, so as to move them in 65 both directions, and thereby open as well as close the jaws D. (See Fig. 4.) The collar G is held from turning on the hub c by a spline or feather g , and is adjusted thereon by means of the nut g' . The longer arms of levers F F 70 are connected by links $h h$ with a collar H, which is loosely mounted upon the usual sliding sleeve I. The collar H, having radial play upon the sleeve I, equalizes the force exerted through the connecting-levers upon the jaws 75 D, causing an equal and uniform engagement thereof with the rim of the friction-driver.

To take up play or wear on the friction-surfaces of the clutch and to cause the jaws to grip more or less tightly the interposed rim 80 of the friction-driver, the collar G is moved by means of the nut g' axially in the required direction on the hub of the jaw-carrier, thereby adjusting by a single operation the fulcrums of levers F, so that when the sleeve I 85 is brought into the position in which it is shown in Fig. 1 the levers F, acting upon and through the levers E, will properly close the jaws upon the rim of the friction-driver.

The clutch shown in Figs. 1 and 2 is particularly designed for connecting or coupling shafts in line with each other; but with little or slight modification the same construction may be employed in connection with a pulley, as shown in Fig. 3. For this purpose the jaw- 90

carrier A is formed or provided with a belt-
rim a' , and is loosely mounted upon the same
shaft on which the jaw-carrier C is keyed,
being held in place thereon by the hub of the
5 jaw-carrier and a collar (not shown) fixed to
the clutch-shaft on the opposite side.

Referring to Fig. 4, the levers F' are con-
nected by links f' with the levers E, which
10 are fulcrumed to the jaw-carrier and are piv-
oted on opposite sides of their fulcrums to the
jaws D, so as to positively open as well as
close the jaws.

I claim—

1. In a friction-clutch, the combination,
15 with the friction-wheel having a laterally-
projecting rim and radially-movable jaws
adapted to grip said rim, of levers adapted to
close said jaws and fulcrumed to an axially-
adjustable collar, whereby play or wear may
20 be taken up by a single operation, substan-
tially as and for the purposes set forth.

2. In a friction-clutch, the combination,
25 with gripping mechanism, substantially as
described, of operating-levers and a collar
which has radial play upon the clutch-shaft,
whereby equal and uniform engagement of the
friction-surfaces of the clutch is produced,
substantially as and for the purposes set forth.

3. In a friction-clutch, the combination,
30 with gripping mechanism, substantially as
described, of an axially-adjustable collar, op-
erating-levers fulcrumed to said collar, where-
by play and wear are taken up, and a radially-
movable collar with which the operating-le-
vers are connected, whereby equal and uni-
35 form engagement of the friction-surface is

produced, substantially as and for the pur-
poses set forth.

4. In a friction-clutch, the combination,
40 with clutch mechanism comprising a friction-
wheel having a laterally-projecting rim, of a
jaw-carrier provided with radially-adjustable
jaws, and levers fulcrumed to said carrier and
45 connected with said jaws so as to simulta-
neously close the same, a collar mounted and
axially-adjustable upon the clutch-shaft, bell-
crank levers fulcrumed to said collar and ar-
ranged to actuate the levers fulcrumed to said
carrier, a sleeve movable axially on the clutch-
shaft, and a collar mounted and having ra-
50 dial play upon said sleeve and linked to said
bell-crank levers, substantially as and for the
purposes set forth.

5. In a friction-clutch, the combination,
55 with a driver having a laterally-projecting
rim and gripping mechanism comprising a
carrier, radially-movable jaws mounted upon
said carrier, and levers fulcrumed to said car-
rier and connected with said jaws so as to
close the same against the rim of the driver,
60 of a collar adjustable axially upon the clutch-
shaft, and levers fulcrumed to said collar so
as to connect with and actuate the levers on
said carrier, substantially as and for the pur-
poses set forth.

In testimony that I claim the foregoing as
my own I affix my signature in presence of two
witnesses.

HANS P. CLAUSSEN.
